GAME BOARD

Theo M. Leonard, 8620 44th St., Lyons, Ill. 60534

Filed May 3, 1968, Ser. No. 11,780

Term of patent 7 years

Int. Cl. D21—01

U.S. Cl. D34—5

FIG. 2.

FIGURE 1 is a top side or plan view of my new design of a game board, the surface applied shade lines on certain of the square shaped stations and on the circularly shaped stations representing contrastingly different colors, and

FIGURE 2 is an edge view of the game board.

I claim:

The ornamental design for a game board, substantially as shown and described.
